UNITED STATES PATENT OFFICE.

WILLIAM S. WESTON, OF COLUMBIA, SOUTH CAROLINA.

DEVICE FOR REMOVING PULLEYS FROM SHAFTS.

Application filed January 16, 1922. Serial No. 529,795.

To all whom it may concern:

Be it known that I, WILLIAM S. WESTON, a citizen of the United States, and residing at Columbia, Richland County, State of South Carolina, have invented certain new and useful Improvements in Devices for Removing Pulleys from Shafts, of which the following is a specification.

The present invention relates to devices for removing pulleys from shafts, crank pins from cranks, and in fact for securing relative movement between a shaft and any article or device which is frictionally held on said shaft.

The object of the invention is to provide a device of this character which is of simple construction and light in weight, while at the same time is powerful in action and can overcome great frictional force opposing the movement of a pulley, for instance, along a cylindrical shaft on which it is tightly fitted. Another object of the invention is to provide such a device which may be placed on a shaft at any point along its length to move or shift a pulley mounted thereon, the device not being necessarily put on the shaft over the end. In certain cases it is desired to exert a pulling force upon a wheel or pulley to move it along a shaft where it is impossible to position the device in close proximity to the pulley to be moved. A device formed in accordance with one form of the present invention is adapted to be placed on the shaft at a distance from the pulley and to be operatively connected thereto by means of rods so that the pulling may be conveniently effected when the device is necessarily located at some distance from the object to be shifted.

The invention may be made in various forms and one embodiment is illustrated in the accompanying drawings, in which:

Figure 1 is a side elevation, partly broken away, of the invention as applied to a shaft and in position to move the hub of a pulley longitudinally along the shaft;

Figure 2 is a section on line 2—2 of Figure 1;

Figure 3 is a side elevation of the collar which comprises one portion of the device;

Figure 4 is a section through one form of tapered bushing used;

Figures 5 and 6 are side and end elevations respectively of a second form of tapered bushing;

Figure 7 is an edge view of a modified form of collar;

Figure 8 is a longitudinal section through the same;

Figure 9 is an elevation of the same showing its working face;

Figure 10 is a side elevation of portion of a shaft showing the device in position to exert a pulling force on a member mounted on the shaft, and

Figure 11 an end elevation of the same as seen from the right (Fig. 1).

A shaft is indicated at 10 and the hub of a wheel or pulley which is frictionally secured to the shaft is indicated at 11. Resting against one face of the hub of the pulley is a protecting plate or washer 12 which insures that this face of the pulley hub is not injured or bruised during the shifting operation. Supported upon shaft 10 adjacent washer 12 is a bushing 13 which is longitudinally split at 14 so that it may be expanded or contracted. The outer surface of this bushing is frusto-conical, the bushing tapering in axial cross section toward the washer 12. Preferably a sheet of paper, cloth or similar material 15 is interposed between the bushing and the shaft. The outer frusto-conical surface of the bushing is lubricated and fits within a correspondingly tapered central aperture in the collar 16. The face of the collar 16 which lies adjacent washer 12 has two inclined grooves 17 thereon and these grooves receive wedges 18, which bear against both the collar 16 and the washer 12.

Downward movement of the wedges of course will cause a preliminary movement of the collar 16 away from the hub but this movement immediately causes bushing 13 to grip shaft 10, so that this bushing serves as an abutment preventing further movement of collar 16 along the shaft. Further downward force exerted on the wedges 18 will overcome the frictional resistance to relative movement between the hub 11 and shaft 10 and the hub will move along the shaft. When the wedges have been driven down as far as possible, they are removed, the collar 16 advanced toward the hub and the bushing 13 also advanced to have a snug fit with the collar, and the wedges again driven down to move the hub a further distance along the shaft. This operation may be repeated as many times as are necessary to obtain the

desired movement of the hub, and the mechanical advantage of the device is such that it is able to overcome very great frictional resistance. Instead of advancing the bushing 13 after each downward movement of the wedges a shim, or shims, may be placed, in addition to the washer 12, between the collar and the hub 11 to narrow the gap into which the wedges are driven. This 10 saves considerable time in operation.

The device illustrated in Figures 1, 2, 3 and 4 is adapted to be placed over the end of the shaft, the collar 13 being one integral piece. It is sometimes impossible, 15 due to the presence on the shaft of additional pulleys or other obstructions, to place the collar over the end in this manner. In such case the form of the device illustrated in Figures 5 to 9 inclusive may be employed.

20 The tapered bushing illustrated in Figures 5 and 6 is split longitudinally along diametrically opposite lines. The junction line between the two halves is not straight but each half has a shoulder with a transverse 25 face which abuts against a similar face on the opposite half to prevent relative longitudinal movement between the two halves of the bushing in the operation of the device, the shoulders of each half facing in opposite directions.

As can be seen in Figure 6 the adjacent 30 edges of the two halves overlap and there is ample clearance at 14' to permit a limited radial movement of the bushing. The 35 collar illustrated in Figures 7, 8 and 9 comprises two portions 18 and 19 hinged together by a pin 20. A second pin 21 is provided for locking the opposite ends of the two portions together after the collar 40 has been placed around the shaft. Inclined faces 22 constitute bearing surfaces for the wedges and the operation of the device, when once it is placed in position, is exactly the same as in the first described 45 form of the invention.

The collar 18 is provided with holes 23 which are diametrically opposed to each other and are equidistantly spaced from the center. These holes or apertures are 50 adapted to receive rods or bars such as illustrated at 24, which rods or bars may connect a member in advance of the collar, such as the U shaped member 25, to a pulley or other object at some distance from the 55 pulling device, when it is not possible to position this device adjacent the object to be moved. When these rods are being used it is possible to exert a pulling force on an 60 object mounted on the shaft at some distance from the collar, such as ring 26, shown in Figure 10.

To those skilled in the art it will be apparent that still other modifications of the invention might be made and that the invention is not limited in its scope to the de-

vices described. The many advantages of the device will also be recognized.

Having thus described my invention what is claimed as new and desired to be secured by Letters Patent is:

1. A device of the class described including, in combination, a collar, means for engaging a shaft to prevent movement of the collar in one direction, and means to cooperate with the collar and movable transversely of the shaft, to exert equal and oppositely directed forces on the collar and the object to be moved. 70

2. A device of the class described including in combination, a collar, a wedge member for engaging a shaft to prevent movement of the collar in one direction, and means adapted to be inserted between the collar and the object to be moved, to exert equal and oppositely directed forces 80 on the collar and said object. 85

3. A device of the class described including in combination, a collar having an aperture to receive a shaft, the wall of the aperture being inclined to its axis, a wedge member to engage the wall of the aperture and the shaft to prevent movement of the collar in one direction, and means to cooperate with the collar and movable transversely of the shaft to exert equal and oppositely directed forces on the collar and object to be moved. 90 95

4. A device of the class described including in combination, a collar having a tapering aperture to receive a shaft, means adapted to enter said aperture in addition to the shaft, to engage the collar and shaft to prevent movement of the collar in one direction, and wedge means to cooperate with the collar and movable transversely 100 of the shaft, to exert equal and oppositely directed forces on the collar and the object to be moved. 105

5. A device of the class described including in combination, a collar having a tapering aperture to receive a shaft, a wedge adapted to enter said aperture in addition to the shaft to engage the collar and shaft to prevent movement of the collar in one direction, and wedge means to cooperate with the collar and movable transversely of the shaft, to exert equal and oppositely directed forces on the collar and the object to be moved. 110 115

6. A device of the class described, including in combination, a collar having a tapering opening therethrough of circular cross section to receive a circular shaft, a sleeve bushing having a correspondingly tapering outer surface and a cylindrical inner surface, adapted to enter the tapering opening in the collar and to engage the shaft to prevent movement of the collar in one direction, and wedge means to cooperate with the collar and movable transversely of the 120 125 130

shaft, to exert equal and oppositely directed forces on the collar and the object to be moved.

7. A device of the class described, including in combination, a collar having a tapering opening therethrough of circular cross section to receive a circular shaft, a sleeve bushing having a correspondingly tapering outer surface and a cylindrical inner sur-

face, adapted to enter the tapering opening in the collar and to engage the shaft to prevent movement of the collar in one direction, said bushing being longitudinally split so as to be contractible and expandible, and wedge means to cooperate with the collar and movable transversely of the shaft, to exert equal and oppositely directed forces on the collar and the object to be moved.

8. A device of the class described including in combination, a collar adapted to fit around a shaft and comprising two separate portions adapted to be rigidly secured together, means for engaging the shaft to prevent movement of the collar in one direction, and wedge means to cooperate with the collar and movable transversely of the shaft, to exert equal and oppositely directed forces on the collar and the object to be moved.

9. A device of the class described, including in combination, a collar having an aperture to receive a shaft, openable to receive the shaft and closable to completely encircle the shaft, means for engaging the shaft to prevent movement of the collar in one direction, and wedge means to cooperate with the collar and movable transversely of the shaft, to exert equal and oppositely directed forces on the collar and the object to be moved.

10. A device of the class described including in combination, a collar adapted to fit around a shaft and comprising two portions hinged together so as to be removable from the shaft, means for engaging the shaft to prevent movement of the collar in one direction, and wedge means to cooperate with the collar and movable transversely of the shaft, to exert equal and oppositely directed forces on the collar and the object to be moved.

11. A device of the class described including in combination, a collar adapted to fit around a shaft and comprising two por-

tions hinged together so as to be removable from the shaft, means to lock said portions rigidly together, and means for engaging the shaft to prevent movement of the collar in one direction, and wedge means to cooperate with the collar and movable transversely of the shaft, to exert equal and oppositely directed forces on the collar and the object to be moved.

12. A device of the class described including in combination, a collar member adapted to fit around a shaft, a second member adapted to also fit around the shaft adjacent the first member, means for securing one of said members to the shaft, means insertable between said members to effect relative movement thereof, and means for connecting one of said members to a distant object mounted on the shaft.

13. A device of the class described including in combination, a collar member adapted to fit around a shaft, a second member adapted to also fit around the shaft adjacent the first member, means for securing one of said members to the shaft, means insertable between said members to effect relative movement thereof, and rods secured to one of said members and extending toward and past the other member for connecting the first member to a distant object mounted on the shaft.

14. A device of the class described, including in combination, a collar adapted to fit around a shaft, a U shaped member adapted to fit around the shaft adjacent the collar, means for securing the collar to the shaft, means insertable between said collar and member to effect relative movement thereof, and rods for connecting the U shaped member to a distant object mounted on the shaft.

15. A device of the class described, including in combination, a collar adapted to fit around a shaft, and having apertures therein, a U shaped member adapted to fit around the shaft adjacent the collar, means for securing the collar to the shaft, and rods for connecting the U shaped member to a distant object mounted on the shaft, said rods passing through the apertures in the collar.

In testimony whereof I hereunto affix my signature.

WILLIAM S. WESTON.
